UNITED STATES PATENT OFFICE.

MAX F. GARLIN, OF CHICAGO, ILLINOIS.

MARGINAL FOLDING DEVICE.

1,223,575.

Specification of Letters Patent. Patented Apr. 24, 1917.

Application filed December 18, 1915. Serial No. 67,530.

To all whom it may concern:

Be it known that I, MAX F. GARLIN, a citizen of the United States, and a resident of the city of Chicago, in the county of Cook and State of Illinois, have invented certain new and useful Improvements in Marginal Folding Devices; and I do hereby declare that the following is a full, clear, and exact description of the same, reference being had 5 to the accompanying drawings, and to the numerals of reference marked thereon, which form a part of this specification.

Great difficulty has been experienced heretofore in properly folding over the margin 15 of a piece of fabric so as to permit the fabric piece to be readily stitched in place, particularly in the case of pockets for garments wherein the piece of fabric is sewed to the garment through the folded margin of the 20 fabric.

This invention relates to a machine into which the piece of fabric, which has been cut according to the pattern, is placed, and when operated upon by the machine has its 25 margin folded and creased inwardly, so that attachment of the piece of fabric to a garment by stitching through said folded margin becomes a simple and convenient operation.

30 It is an object of this invention to construct a machine for folding and creasing the margin of a piece of fabric according to a predetermined shape wherein the parts are adjustable for operation upon pieces of fabric of different size, though similar in shape.

It is also an object of this invention to 35 construct a pocket fabric marginal folding and creasing machine wherein a presser plate is actuated downwardly between folder bars to operate in conjunction therewith, folding the margin of the fabric inwardly while slightly heating the same during the 40 operation so that a more or less permanent crease is made in the fabric to define the folded margin to facilitate attachment of the 45 fabric to a garment by stitching through said folded margin.

It is furthermore an important object of 50 this invention to construct a pressing machine adapted to fold the margin of a piece of fabric of predetermined shape inwardly, and crease the same by a single pressing operation of the parts of the mechanism.

It is finally an object of this invention to 55 construct an improved type of folding, creas-

ing and pressing machine with the parts so arranged as to permit easy access thereto to position and remove a piece of fabric in and from the machine, and with the parts adjustable to accommodate and operate upon 60 pieces of fabric of different size.

The invention (in a preferred form) is illustrated in the drawings and hereinafter more fully described.

In the drawings:

Figure 1 is a front elevation of a machine 65 embodying the principles of my invention.

Fig. 2 is an enlarged fragmentary sectional view taken on line 2—2 of Fig. 1.

Fig. 3 is a top plan view of the presser 70 table of the machine, taken on line 3—3 of Fig. 2.

Fig. 4 is a plan view of the steaming ring mounted beneath the presser table.

Fig. 5 is a fragmentary detail view illustrating a driving disk with a connecting link pivoted thereon which forms a part of the 75 machine.

Fig. 6 is a fragmentary bottom plan view of the presser table.

Fig. 7 is a sectional detail taken on the line 80 7—7 of Fig. 3 and showing the presser shaft, its spider arms and the presser plate only.

Fig. 7^a is a similar view taken on the same line as Fig. 7, and showing the folding and 85 creasing devices which coöperate with the parts shown in Fig. 7.

Fig. 8 is a sectional view on the same line with Figs. 7 and 7^a, but showing the parts in said figures in coöperating relation.

Fig. 9 is a view similar to Fig. 8, showing 90 the parts in another position of adjustment.

Fig. 10 is an enlarged detail section taken on line 10—10 of Fig. 7^a.

Fig. 11 is an enlarged detail section taken 95 on line 11—11 of Fig. 7.

Fig. 12 is an enlarged detail sectional view taken on line 12—12 of Fig. 7.

Fig. 13 is a fragmentary detail section taken on line 13—13 of Fig. 3.

Fig. 14 is a detail view of one of the actuating links for the folder devices.

As shown in the drawings:

The frame of the machine consists of a pair of uprights 1 and 2, respectively, reinforced and joined by a transverse member 3, and with a table 4, supported on and between said uprights. Bearings 5, are secured at the upper ends of the uprights 1 and 2, and journaled therein is a driving shaft 6, 105 110

provided with a disk 7, secured thereon, having a cam groove afforded between ridges 8, formed on said disk. Connected on one end of said shaft 6, is an automatically actuating clutch denoted as a whole by the reference numeral 9, which acts to disengage itself after one revolution of the driving pulley 10, provided on said shaft 6, in a familiar manner well known on machines such as punch presses and the like, and since the details of which form no part of this invention, no details thereof are entered into here.

For the purpose of actuating said clutch 9, a foot lever 11, is provided, mounted on the floor adjacent the base of the frame member 2, and is connected by means of a long actuating rod 12, to said clutch. Slidable vertically through a guide aperture provided in the cross frame member 3, is a presser plate shaft or rod 13, and journaled horizontally on one side at the upper end thereof is a roller 14, adapted to track in the cam groove between the ridges 8, on said disk 7. Secured on or integral with the lower end of the vertical presser shaft 13, are four slotted spider arms 15, reinforced at their inner ends by a web 16. Mounted beneath the arms 15, is a presser plate, the outline of which is substantially the same as that of the piece of fabric to be folded and creased, said presser plate consisting of a base plate member of wood or metal, denoted by the reference numeral 17, and with a thin sheet or plate of metal 18, secured therebeneath, with the margin thereof projecting beyond the edge of the base member 17, almost entirely therearound, as clearly shown in Figs. 3, 8 and 9. Said presser plate 17-18, is yieldably connected beneath the arms 15, of the spider, in the following manner. For this purpose bolts 19, are threaded into the top plate 17, and extend slidably through bushings 20, held clamped in the slots in said arms 15, by small collars 21, and are further provided with nuts 22, which hold the bolts 19, against withdrawal through said bushings 20.

Coiled around each of said bolts 19, is a spring 23, one end of which bears upon the upper surface of the plate 17, and the other end of which bears beneath the lower end of the bushing 20, said springs acting normally to impel and hold the presser plate 17-18, downwardly away from the supporting spider arms 15. Resilient presser feet are also provided at the outer ends of the arms 15, and for this purpose, as shown in detail in Fig. 12, a bushing 24, is held clamped in the slot of each of the arms 15, by a threaded collar 25, and slidably through said bushing is a rod or bolt 26, having a flat bearing foot 27, on its lower end, on the upper surface of which seats a coiled compression spring 28, normally impelling the

same downwardly, and a nut 29, is threaded on the upper end of said bolt to retain the same from withdrawal through said bushing by the stress of said spring.

Yieldably mounted upon the table 4, conforming to the outline of and partly surrounding the presser plate 17-18, are folding and creasing devices comprising curved bars 30, which are cored out at the points 31, in their upper surface to receive water 75 poured therein for cooling purposes. As clearly shown in Fig. 13, the inner side of each of said bars 30, is cut away to afford a continuous tapered edge 32, adapted to engage beneath the margin of the fabric and 80 crease the same upwardly around the outer edge of the presser plate during the operation of the device. The presser feet 27, before described, adjustably mounted upon the spider arms 15, are so disposed as to contact and bear upon the bars 30, to force the same downwardly, and said bars 30, in turn are yieldably as well as slidably supported in the following manner.

For this purpose grooved bosses 33, are 90 formed on the under surface of the table 4, as clearly shown in Figs. 6 and 10, and slidably in the groove of each of said bosses are flat bars or links 34, one of which is shown in Fig. 14, each having a plurality of apertures 95 35, near one end thereof to receive threaded thereinto the lower end of an upright bolt 36, as shown in Fig. 10. Said upright bolts 36, extend slidably through the respective bars 30, and are adapted to slide in slots 100 provided therefor in the table 4, directly above said bosses 33, said slots being denoted by the reference numeral 37, as shown in Figs. 7, 8, and 9. Coiled around each of said upright bolts 36, and seated in a recess provided on the under side of said respective bars 30, are springs 38, which bear upon the upper surface of the table 4, thus normally maintaining said curved bars 30, elevated therefrom. Slots 39, parallel to said slots 105 37, are also provided in the table 4, as clearly shown in Fig. 6, and sliding in each is the rectangular shaped end of one of two guide bolts 40, which extend slidably through the bars 30, and compression springs 41, are 115 coiled therearound, bearing upwardly beneath the bars 30, and downwardly upon the table 4, to normally maintain said bars 30, elevated therefrom. For the purpose of drawing said curved bar 30, slightly inwardly at the proper time during the operation of the machine, a disk 42, is pivotally mounted upon the under surface of the table 4, and is provided with similar cam slots 43, which are slightly angled, as clearly shown 125 in Fig. 6, and journaled on the inner ends of each of the links or bars 34, are rollers 44, which fit into said respective cam slots 43, so that by an oscillation of said disk 42, said links 34, are caused to slide in the recesses 130

therefor in the bosses 33. Mechanisms are provided driven from the drive shaft 6, for oscillating said disk 42. For this purpose, a small bevel pinion 45, is secured upon the 5 end of the shaft 6, meshing with a bevel pinion 46, secured upon the end of an upright shaft 47; which is journaled in bearings 48, secured upon the frame member 1. On the lower end of said 10 upright shaft is a disk 49, which has pivotally connected thereto a link 50, which is in turn pivoted on said disk 42. Mounted beneath the disk 42, and connecting link 50, is an apertured ring pipe 51, through which steam 15 is admitted, heating and rendering the atmosphere more or less moist in the field of operation of the machine, so that the folding and creasing of the fabric imparts more or less permanency to the fold or crease made 20 therein.

The operation is as follows:

The construction of the driving disk 7, is such that the cam groove afforded between the ridges 8, with each revolution of the disk 25 7, first imparts a descending movement to the presser plate, holding the same slightly spaced above the table 4, for an instant, and then thrusting the same downwardly and holding the same thereagainst for a certain 30 interval, then elevating and holding the presser plate slightly spaced above the fabric and then withdrawing the presser plate to initial elevating position. The pressing or pressure part of the operation is performed during the time that the roller 14, on the upper end of the shaft or rod 13, is in the arc shaped and outwardly offset portion 52, of the cam groove between the ridges 8. Also driven simultaneously with the 35 presser plate at times for proper co-action therewith, are the folder and creasing bars 40 30, which move inwardly guided by the respective slots 37 and 39, such that the tapered edges 32, which engage beneath the fabric, denoted by the reference numeral 53, and shown in Figs. 8, and 9, folds the fabric 45 over the outer margin of the plate 18, from the position shown in Fig. 8, to that shown 50 in Fig. 9. The pressure is transmitted yieldably to said bars 30, from the spider arms 15, with a final downward movement of the upright 13, through the presser feet 27.

The inward movement of said bars 30, is effected by the oscillation of the disk 42, 55 driven from and properly timed with respect to the shaft 6, through the shaft 47, and link 50. An oscillation in one direction of said disk 42, first draws said bars 30, inwardly, so that the tapered edges 32, thereof, engage beneath the margin of the fabric 53, but above the plate 18, as shown in Fig. 8, 60 and then farther inwardly, so as to fold the fabric over the sheet 18, and beneath said tapered edges 32, as shown in Fig. 9, so that 65 the descending spider arms 15, will impart

pressure upon the inwardly folded margin of the fabric through the bars 30.

Immediately after the pressure is released by upward movement of the spider arms 15, the bars 30, move upwardly under the stress 70 of their supporting springs 38, and the reverse oscillation of said disk 42, now takes place, so that the pressure bars 30, are moved outwardly, and after the presser plate 17-18, is elevated away, the fabric operated 75 upon may be removed. The presser plate 17-18, may be detached and replaced by one of smaller area and the bars 30, may be moved inwardly to correspond thereto for operation on pieces of fabric of different 80 size.

I am aware that various details of construction may be varied through a wide range without departing from the principles of this invention, and I therefore do 85 not purpose limiting the patent granted otherwise than necessitated by the prior art.

I claim as my invention:

1. In a machine of the class described, a movable presser plate, a table to receive the 90 fabric to be folded and creased, bars movable inwardly to fold the margin of the fabric over said presser plate, and means operated by the presser plate moving mechanism for imparting pressure toward said table 95 both to said presser plate and to said bars.

2. In a machine of the class described, a movable presser plate, bars adapted to be moved inwardly over said presser plate after a descent of the same, and means operated 100 by the presser plate moving mechanism for imparting yielding pressure to said presser plate and to said bars to thrust the latter downwardly against the presser plate and crease the inwardly folded margin of the 105 fabric therebetween.

3. In a machine of the class described, a table, bars yieldably and slidably mounted thereon, means for moving said bars inwardly toward one another, a presser plate 110 adapted to be moved toward said table to press the fabric placed thereon, and a drive for said presser plate and said bars so timed as to move said bars inwardly over the presser plate to fold and crease the margin 115 of the fabric thereover after the descent of the presser plate, to depress said bars and presser plate simultaneously and to move said bars outwardly and release the same prior to ascent of said presser plate. 120

4. In a machine of the class described, a table, a presser plate mounted thereabove adapted to move downwardly thereon, a yieldable support for said presser plate, bars 125 yieldably mounted upon said table and slidably thereon, a drive to move said presser plate downwardly and thereafter move said bars inwardly, and means to force said bars momentarily downwardly upon said presser plate, said drive acting thereafter to retract 130

said bars after release from said presser plate and move said presser plate upwardly to initial position.

5. In a machine of the class described, a frame, a table mounted thereon, a drive shaft mounted at the upper end of the frame, a presser plate vertically movable in said frame and yieldably mounted, a cam mounted on said drive shaft and adapted to impart movement to said presser plate to lower and raise the same, and bars yieldably and slidably mounted upon said table and adapted to be moved inwardly over the mar-

gin of said presser plate after the descent of the latter to fold the margin of a fabric thereover, said bars being adapted to be thrust downwardly thereon and thereafter retracted to permit elevation of said presser plate to initial position. 15

In testimony whereof I have hereunto 20 subscribed my name in the presence of two subscribing witnesses.

MAX F. GARLIN.
